CLAIM

I claim the ornamental design for relaxer bench, as shown.

DESCRIPTION

FIG. 1 is a perspective view of a relaxer bench, showing my new design, wherein the extended portion is in a lowered position;

FIG. 2 is a perspective view of the relaxer bench, wherein the extended portion is in a raised position, the broken line structure being shown for illustrative purposes only and forming no part of the claimed design;

FIG. 3 is a left side elevational view of the design of FIG. 1;

FIG. 4 is a right side elevational view thereof;

FIG. 5 is a front elevational view thereof;

FIG. 6 is a rear elevational view thereof;

FIG. 7 is a plan view thereof; and,

FIG. 8 is a bottom view thereof.
